[57] **CLAIM**

The ornamental design for a toilet paper holder, as shown and described.

DESCRIPTION

FIG. 1 is a top perspective view of a toilet paper holder showing my new design;

FIG. 2 is a front elevational view thereof;

FIG. 3 is a side elevational view taken from the left of FIG. 1;

FIG. 4 is a top plan view thereof; and

FIG. 5 is a bottom plan view.

The rear of the device is plain apart from the holes visible in FIG. 2.

FIG. 1

FIG. 2

FIG. 3

FIG. 4

FIG. 5
